UNITED STATES PATENT OFFICE.

WILLIAM F. GRADOLPH, OF TOLEDO, OHIO, ASSIGNOR TO THE DE VILBISS MANUFACTURING COMPANY, OF TOLEDO, OHIO, A CORPORATION OF OHIO.

PRESSURE-REGULATOR.

1,318,863.

Specification of Letters Patent. Patented Oct. 14, 1919.

Application filed November 18, 1918. Serial No. 263,000.

To all whom it may concern:

Be it known that I, WILLIAM F. GRADOLPH, a citizen of the United States, and a resident of Toledo, in the county of Lucas and State of Ohio, have invented a certain new and useful Pressure-Regulator; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to fluid pressure control means for use in connection with spraying apparatus, and more particularly for use in connection with paint spraying apparatus in which liquid paint is contained in a substantially air tight receptacle and is forced therethrough by air pressure to an air brush or spraying device, which is also supplied with air under pressure to assist in discharging the liquid therefrom in 20 spray form, as well understood in the art.

25 In the use of apparatus of this class, it is customary to maintain the air within the paint receptacle and at the air brush under different predetermined pressures, and the 30 primary object of my invention is the provision of a simple and efficient and improved pressure regulating means for such purpose. Further objects and advantages of the invention will be apparent from the following detailed description thereof.

35 While the invention in its broader aspect is capable of embodiment in numerous forms, a preferred embodiment thereof is illustrated in the accompanying drawings, 40 in which,

Figure 1 is a side elevation of an apparatus embodying the invention, with the receptacle with which it is associated in section. Fig. 2 is a top plan view thereof. Fig. 3 is an enlarged central vertical section of the pressure regulating means with parts in full. Fig. 4 is an enlarged sectional detail of a portion thereof. Fig. 5 is a top plan view of the body member 45 of the apparatus with the end caps removed and a part broken away. Figs. 6 and 7 are

sections thereof taken, respectively, on the lines 6, 6 and 7, 7 in Fig. 5, and Fig. 8 is an end view thereof.

Referring to the drawings, 1 designates 55 a closed air tight receptacle for the paint, or other matter to be sprayed, 2 the removable top closure member therefor, and 3 the pressure regulator head or body member, which is threaded at its bottom in an opening 60 provided therefor in the closure member.

The head 3 is provided in its central portion with a main pressure chamber 4 and at the opposite sides of said main chamber with the two secondary or reduced pressure 65 chambers 5 and 6. Valve controlled communication is provided between the main chamber 4 and each secondary chamber. In the present instance, the wall between the main chamber 4 and each secondary chamber 70 is provided with an opening 7 in which is threaded a bushing 8 forming a seat for a check valve 9 and a guide for its stem 10, and also forming a communicating passage 11 between the main and respective secondary chambers. The valve 9 seats under 75 main chamber pressure against the inner end of its bushing 8, and its stem projects outward through the bushing into the respective secondary chamber. The valve is normally held seated by a coiled tension spring 12, which encircles the outer end portion of the valve stem and has its inner end-thrust against the outer end of the bushing 8 and its outer end-thrust against a tension adjusting nut 13 on the outer end of the stem. 80

The outer side of each secondary pressure chamber 5, 6 is closed by a diaphragm 14, which is clamped to the respective end of the head 3 by a cap 15 screwed thereon. 90

Each cap 15 contains a spring chamber 16 open at its inner end to the diaphragm 14, and a coiled compression spring 17 is disposed in this chamber with its axis substantially alined with the adjacent valve stem 10 95 and with its inner end provided with a plunger 18 in thrust contact with the central portion of the diaphragm in opposition to the valve stem 10, which is intended to have contact with the inner side of the diaphragm, as shown. A tension adjusting screw 19 is threaded through the outer end 100

of the cap 15 and in contact at its inner end with a member 20 against which the spring has its outer end thrust.

The main pressure chamber 4 has a supply passage 21 (Fig. 6) in communication with a source of air supply under pressure through a valve controlled tube 22 (Figs. 1 and 2). The secondary pressure chamber 5 has an outlet passage 23 in communication 10 with the interior of the receptacle 1, and the secondary pressure chamber 6 has communication with an outlet passage 24, which, in the present instance, extends entirely through the head 3, crosswise thereof, and 15 has valve controlled tubes 25 and 26 leading from its opposite ends to respective air brushes (not shown) to supply air under predetermined pressure thereto, so that either or both of the air brushes may be 20 used at the same time.

A liquid tube 27 is threaded into the bottom of the head 3 and extends downward therefrom into the receptacle 1 to near its bottom, and communicates at its upper end 25 through a passage 28 with a cross passage 29 in the head. Valve controlled liquid tubes 30 and 31 lead from the opposite ends of the passage 29 to the air brushes to which the respective air tubes 25 and 26 lead. 30 A passage 32 extends down through the head 1 with its lower end in communication with the interior of the receptacle 1. A safety valve 33 is threaded into the upper end 34 thereof and a relief valve 35 is 35 threaded into a side opening 36 thereof.

The air pressure in the receptacle is determined by a gage 37, which is threaded into a socket 38 in the head top, which socket is in direct communication with the 40 head through the passage 32 and a by-pass 39 connecting said socket and passage. The air pressure in the secondary chamber 6 is determined by a gage 40, which connects with said chamber through an opening 41 45 in the head top.

In order to cause the air pressure which enters the receptacle 1 from the chamber 5 to agitate the liquid, a tube 42 extends from the passage 23 down into the receptacle 50 and terminates near the bottom thereof in a horizontally-disposed coil or angled portion 43, which is perforated to discharge the air under pressure in a plurality of streams into the bottom portion of the liquid 55 contained in the receptacle. The coupling 44 between the tube 42 and head passage 23 is provided with a check-valve 45 in the air supply passage, which permits only an outward flow of fluid therethrough, and said 60 coupling is also provided with a lateral passage 46 in communication with the upper portion of the receptacle interior and normally closed by an inwardly opening check valve 47. This check valve is adapted to 65 open under receptacle pressure when the

pressure in the coupling passage above the valve 45 is less than the pressure in the receptacle, which condition would be present if the main supply valve were closed and the stored up pressure in the receptacle not relieved by leakage or an opening of the relief-valve 35. The purpose of the check-valve 45 in the connection between the air chamber 5 and interior of the receptacle is to prevent air pressure within the receptacle from causing a backing up of the paint through the tube 45 and into the chamber 5 when the pressure within said chamber has been relieved by a closing of the main supply valve.

In the use of my invention, it will be understood that the pressure in the main chamber 4 of the regulating head is substantially the same as the pressure at the source of supply, due to the valve passage connecting the same being open, and that the springs 17 normally press the diaphragms 14, with which they coact, inward, and maintain the check valves 9 open due to the contact of the outer ends of the valve stems 80 with the inner sides of the diaphragms. The valves 9 being open permits the air under pressure to enter both secondary chambers 5 and 6 from the main chamber 4 and when the pressure in each secondary 95 chamber is sufficient in conjunction with the springs 12 on the valve stems to overcome the tension of the respective spring 17, the diaphragms 14 will be forced outward and permit a closing of the associated valves. 100 It is evident that the pressure required in the secondary chambers 5 and 6 to permit a closing of the respective valves may be regulated to a nicety by adjusting the tension of the respective springs which is accomplished by turning the screws 19. The pressure in the chamber 5 is regulated to suit the pressure desired in the receptacle 1 and is determined by the indicator gage 37, which is in direct connection with the 105 interior of the receptacle through the socket 38, by-pass 39 and passage 32 in the head. The pressure in the chamber 6 is regulated to suit the air pressure desired at the air brushes employed and is determined by the 110 gage 40, which is in communication with the chamber 6.

I wish it understood that my invention is not limited to any specific construction, arrangement or form of the parts, as it is 115 capable of numerous modifications and changes without departing from the spirit of the claims.

Having thus described my invention, what I claim as new, and desire to secure by Letters Patent, is,—

1. In an apparatus of the class described, the combination with a liquid receptacle and an air brush in connection therewith, of a pressure regulator head having a main pres- 130

ture chamber in communication with a source of fluid pressure supply, two secondary pressure chambers each having communication with said main chamber and one 5 having communication with the interior of said receptacle and the other having communication with the air brush, a diaphragm in each secondary chamber, a valve normally closing the communication between 10 each secondary chamber and the main chamber and having its stem in connection with the diaphragm whereby an inward movement of the diaphragm effects an opening of the valve, adjustable pressure regulating 15 means coating with the outer side of each diaphragm to resist an outward valve closing movement thereof, a pressure gage carried by said head in direct communication with the interior of the receptacle, and a 20 pressure gage carried by the head in direct communication with the secondary chamber having communication with the air brush.

2. In an apparatus of the class described, the combination with a receptacle and an 25 air brush, of a pressure head in connection with the receptacle having a centrally disposed main pressure chamber in communication with a source of supply and secondary pressure chambers at opposite sides of the 30 main chamber in communication therewith, a diaphragm in each secondary chamber, a normally closed valve between each secondary chamber and the main chamber to close the communication therebetween and having 35 its stem in connection with the respective diaphragm whereby an inward movement of the diaphragm opens the valve, separate adjustable means for exerting a predetermined inward valve opening pressure on each dia- 40 phragm, said head having a passage in communication with the interior of the receptacle, a pressure gage and a valve in connection with said passage, a pressure gage in connection with the air pressure communi- 45 cating secondary chamber, and a liquid tube extending from said head down into the receptacle and having communication through the head with the air brush.

3. In an apparatus of the class described, 50 the combination with a receptacle, of a pressure head connected thereto, said head having a main pressure chamber in communication with a source of supply and two secondary pressure chambers in connection 55 with said main chamber and one in communication with the interior of said receptacle, a normally closed valve in the communication between each secondary chamber and the main chamber, separate adjustable 60 means coating with each valve to open the same and operable by a predetermined pressure in the respective secondary chamber, augmented by the normal closing tendency of the valve, to permit a closing of the valve, 65 said head having two cross passages therein,

each in communication at opposite ends with separate spraying devices and one having communication with the other secondary chamber than that which is in communication with the receptacle, a liquid tube ex- 70 tends down into the receptacle from said other cross passage, a pressure gage carried by said head and in communication through a part of the head with the interior of said receptacle, and a secondary pressure gage 75 carried by the head and in communication with the secondary chamber having connection with one of said cross passages.

4. In an apparatus of the class described, a receptacle, a pressure head associated therewith and having a main pressure chamber in communication with a source of fluid pressure supply and two secondary pressure chambers in communication with a main chamber and one in communication with the 80 interior of the receptacle and the other adapted to have communication with a spraying device, a valve normally closing the communication between each secondary and the main chamber, separate adjustable 85 means coating with each valve to open the same and operable by a predetermined pressure in the respective secondary chamber, augmented by the normal closing tendency of the valve, to permit a closing of the valve, 90 a tube interposed in the communication between one of the secondary chambers and the interior of the receptacle with which it connects, said tube extending down into the receptacle to discharge air under pressure 95 in the bottom portion thereof, said tube having an outwardly opening check valve in its passage way and an inwardly opening check valve above said outwardly opening valve and adapted to open communication between 100 the interior of the receptacle and the tube passage when the pressure in the tube above the first check-valve is less than the pressure in the receptacle.

5. In combination, an air tight receptacle, 110 means forming a passage which opens communication between a source of air pressure supply and the lower portion of said receptacle to discharge air under pressure into a liquid contained in the receptacle and also 115 forming a by-passage between said main passage and the upper portion of said receptacle interior, an outwardly opening check-valve in said main passage below the by-passage, an inwardly opening check-valve in said by-passage and a shut off valve in said main passage above both said check-valves.

6. In a pressure regulator, means forming a main pressure chamber in communication 125 with a source of fluid pressure supply, a secondary pressure chamber in communication with a source to be supplied with fluid under pressure, and an opening between said chambers, a bushing fitted in said opening 130

and having a fluid passage therethrough, a valve seating against said bushing within the main chamber and having its stem projected through and guided by the bushing 5 and extending into said secondary chamber, a spring within the secondary chamber having its opposite ends thrust against said bushing and a portion of said stem to normally maintain the valve closed, a dia-

phragm in said secondary chamber against 10 which the outer end of said valve stem co-acts, and pressure regulating means coacting with the outer side of said diaphragm in opposition to the valve stem.

In testimony whereof, I have hereunto 15 signed my name to this specification.

WILLIAM F. GRADOLPH.
